UNITED STATES PATENT OFFICE

LOUIS H. ZEUN, OF CATONSVILLE, MARYLAND, ASSIGNOR OF ONE-THIRD TO JOHN B. ADT AND ONE-THIRD TO ALBERT W. ADT, BOTH OF BALTIMORE, MARYLAND

TOBACCO-STEMMING MACHINE

Application filed February 23, 1928. Serial No. 256,397.

This invention relates to certain improvements in tobacco stemming or stripping machines, and particularly to that type of machine having stem pulling means, leaf conveying means, and a stem engaging means, all of said means co-acting so as to permit the leaves to be properly carried to the stem pulling rollers, in order that the stems may be readily stripped from the leaves.

10. The particular object of this invention is the provision of resiliently yielding rollers, whereby the stems may be grasped and readily pulled from the leaves.

A further object of the invention is the provision of stem pulling rollers, one of which is yieldable vertically so as to engage and accommodate stems of all sizes and strip the same from the leaves in a continuous operation.

20. A still further object of the invention is the provision of a pair of stem pulling rollers journaled in superposed relation and equipped with means at one of their ends, whereby stems of all sizes may be readily fed between the rotating opposing faces of said rollers so that said stems may be easily stripped from their respective leaves.

A still further object of the invention is the provision of a pair of rotatable stem pulling rollers having resilient surfaces and equipped at one of their ends with threaded portions, which constitute a feeding means to urge the stems of the tobacco leaves into and between the opposing contacting faces of said rollers.

30. A still further object of this invention is the provision of a pair of resilient rollers connected together by a suitable drive for simultaneous rotation.

40. Another important object of the invention is the provision of equipping certain ends of the rollers with threads, which threads constitute a positive feeding means to urge the stems between the contacting surfaces of said rollers.

A still further object of the invention is the provision of a pair of stem pulling rollers, one of which is relatively stationary laterally and vertically, while the other is yieldable vertically and laterally to permit stems of various sizes to be urged between the opposing faces of said rollers without fear of crushing or breaking said stems during the pulling or stripping action.

50. A still further object of the invention is the provision of a pair of stem pulling rollers mounted in a suitable bearing, one of which rollers is yieldable vertically in said bearing and is provided with a tensioning device so as to normally urge and hold said rollers in contact with one another.

55. A still further object of this invention is the provision of a pair of stem pulling rollers having one of their ends provided with feeding threads, the threads of the stationary roller being in a continuous plane, while the threads of the opposite roller are tapered outwardly, the purpose of which is to constitute a throat for receiving the stems in their initial movement towards the contacting faces of said rollers.

60. With these and other objects in view, the invention consists in certain novel features, combination and arrangement of parts as will be hereinafter more fully described, illustrated in the accompanying drawings, and claimed.

65. In the drawings, Figure 1 is a fragmentary side elevational view of a tobacco stemming machine, illustrating the assembly of my improved stem pulling rollers;

70. Figure 2 is a transverse sectional view taken on the line 2-2 of Figure 1;

75. Figure 3 is a transverse sectional view taken on the line 3-3 of Figure 1;

80. Figure 4 is a fragmentary detailed view, partly broken away, illustrating the construction of the rollers;

Figure 5 is a transverse sectional view, taken on the line 5—5 of Figure 4;

Figure 6 is a fragmentary side elevational view, illustrating the manner in which the yielding roller moves relatively to the stationary roller;

Figure 7 is a side elevational view, partly broken away, illustrating the machine assembled and ready for use;

Figure 8 is a transverse sectional view through the machine, illustrating the initial movement of the leaf and its contact with the rollers; and,

Figure 9 is a transverse sectional view, illustrating the stem being pulled by the rollers from the leaf, which is a completion of the stripping action.

Referring to the drawings, the numeral 5 indicates a tobacco machine support having the usual traveling apron 6 thereon, upon which the tobacco leaves are placed to permit them to be fed to the machine. The machine is also provided with the usual leaf carrying means 7, which is in the form of an endless conveyor having individual teeth in which the stems of the tobacco leaves rest, and these leaves are held therein by a set of resiliently vertically moving fingers 8. This structure conveys the leaf towards the stem pulling rollers 9 and 10, respectively, so that the stem may be stripped from the leaf during its travel over the table 11.

The rollers 9 and 10, respectively, are the main portion of this invention, as the other structure referred to, particularly the support, apron and table, stem conveying and holding means, is old in the art, and is particularly described in the Louis H. Zeun application Serial No. 210,490, filed August 4, 1927.

The stem pulling roller 9 is journaled in a suitable bearing 12 carried by the support 5 of the machine and is horizontally positioned above said support, and this roller 9 is equipped with a core 13 and a resilient outer cover 14 with a top tapered surface 15. One end of this roller 9 is cylindrical and provided with suitable threads 16, which are in the same plane horizontally and extend beyond the roller 10, as illustrated. The threaded terminal of said roller is journaled in a bracket 17, carried by the machine support 5. The opposite terminal of said roller extends laterally beyond its bearing 12 and is provided with a gear 18, which gear meshes with a gear 19, carried on one end of the roller 10, so that the rotation of said rollers may be simultaneous and the speed thereof the same.

The roller 10 has its gear carrying end mounted in a rocking bearing 20, rocking on an axis transverse to the rollers and this bearing is held by a suitable lag screw 21 to the bearing 12, as clearly illustrated in Figure 2.

The opposite end of said roller is tapered and

provided with threads 21' and its free terminal is journaled, as at 24, in a bearing 25, carried by the rocking bearing 20. The bearings 20 and 25 provide a yoke which permits this roller 10 automatically to be moved vertically with relation to the roller 9, and the purpose of said movement being such as to accommodate stems of various sizes without fear of crushing or breaking action on the stems during the pulling action of the rollers when stripping the stems from the leaves. In the present embodiment the longitudinal axis of the roller 10 is thus permitted angular shift relative to the axis of the roller 9.

The gears 18 and 19, respectively, are driven by a suitable mechanism 26, and it is to be understood that when the stems are fed between the opposing contacting faces of the rollers 9 and 10, respectively, by virtue of the threads 16 and 21', respectively, that the simultaneous rotation of said rollers will pull the stems from the leaves, due to the fact that the stems are gripped between the rollers and the blades abutted against the teeth of the carrier 7 and the yieldable holding members 8.

To provide a means to normally hold the roller 10 in leaf-gripping relation to the roller 9, there is provided on the bearing 20 a tensioning member 27 having a weight adjustable for varying the gripping effect of the rollers on the leaves. This tensioning member is upheld by the yoke 20 and permits the roller 10 to have yieldable vertical movement with relation to the relatively stationary roller 9, so as to permit the stems of various sizes to pass through said rollers without fear of crushing or breaking.

Secured to the machine support 5 adjacent the roller 9, is a chute 28, which chute disposes of the stems "A", when the same are severed from the tobacco leaves "B".

It can be readily seen that when tobacco leaves "B" are fed on the apron 6, that the stems "A" are grasped by the carrier 7 and held therein by the members 8 until said stems engage the threads 16 of the roller 9, when they are immediately conveyed between the opposing faces of the rollers and the stripping action completed.

Having thus described my invention, what I claim as new is:

1. A tobacco stemming machine having, in combination, a pair of rollers adapted mutually to cooperate to grip the stems of the leaves to be stemmed, means adapted to rotate said rollers, means adapted to convey the leaves to be stemmed for cooperating with said rollers to effect stemming, and a rocking bearing in which one of said rollers is journaled for rotation.

2. A tobacco stemming machine having, in combination, a pair of rollers adapted mutually to cooperate to grip the stems of the leaves to be stemmed, means adapted to

- rotate said rollers, means adapted to convey the leaves to be stemmed for cooperating with said rollers to effect stemming and a tensioning weight adjustable to vary the effective gripping cooperative between said rollers. 5
3. A tobacco stemming machine having, in combination, a pair of rollers adapted mutually to cooperate to grip the stems of the leaves to be stemmed, means adapted to 10 rotate said rollers, means adapted to convey the leaves to be stemmed for cooperating with said rollers to effect stemming, each of said rollers having threads at one end for feeding the leaves longitudinally of and relative to the rollers, the threaded surface of one roller being tapered and that of the other 15 projecting outward beyond said tapered surface. 10
4. A tobacco stemming machine having, in combination, a pair of rollers adapted mutually to cooperate to grip the stems of the leaves to be stemmed, means adapted to 20 rotate said rollers, means adapted to convey the leaves to be stemmed, means adapted to 25 to rotate said rollers, means adapted to convey the leaves to be stemmed for cooperating with said rollers to effect stemming, each of said rollers having threads at one end for feeding the leaves longitudinally of and relative to the rollers, the threaded surface of one roller being tapered and that of the other 30 cylindrical. 20
5. A tobacco stemming machine having, in combination, a pair of rollers adapted mutually to cooperate to grip the stems of the leaves to be stemmed, means adapted to 35 rotate said rollers, means adapted to convey the leaves to be stemmed for cooperating with said rollers to effect stemming, and a rocking yoke in which each end of one of said rollers is journaled, the rocking axis of said yoke being adjacent an end of the other roller. 30
6. A tobacco stemming machine having, in combination, a pair of rollers adapted 40 mutually to cooperate to grip the stems of the leaves to be stemmed, means adapted to 45 rotate said rollers, means adapted to convey the leaves to be stemmed for cooperating with said rollers to effect stemming, and an automatically rockable bearing in which one of 50 said rollers is journaled for rotation, each of said rollers having threads at one end for feeding the leaves longitudinally of and relative to said rollers, the rocking axis of said bearing being adjacent an end of the other roller and extending transversely of said rollers. 55
7. A tobacco stemming machine having, in combination, a pair of rollers adapted 60 mutually to cooperate to grip the stems of the leaves to be stemmed, means adapted to 65 rotate said rollers, means adapted to convey the leaves to be stemmed for cooperating with said rollers to effect stemming, and an automatically rockable bearing in which one of 70 said rollers is journaled for rotation, each of said rollers having threads at one end for feeding the leaves longitudinally of and relative to said rollers, the rocking axis of said bearing being adjacent an end of the other roller and extending transversely of said rollers. 75
8. A tobacco stemming machine having, in combination, a pair of rollers adapted mutually to cooperate to grip the stems of the leaves to be stemmed, means adapted to 80 rotate said rollers, means adapted to convey the leaves to be stemmed for cooperating with said rollers to effect stemming, and an automatically rockable bearing in which one of said rollers is journaled for rotation, each of said rollers having threads at one end for feeding the leaves longitudinally of and relative to said rollers, the rocking axis of said bearing being adjacent an end of the other roller and extending transversely of said rollers, the threaded surface of one roller being tapered and that of the other cylindrical. 85
9. A tobacco stemming machine having, in combination, a pair of rollers adapted mutually to cooperate to grip the stems of the leaves to be stemmed, means adapted to 90 rotate said rollers, means adapted to convey the leaves to be stemmed for cooperating with said rollers to effect stemming, and an automatically rockable bearing in which one of said rollers is journaled for rotation, each of said rollers having threads at one end for feeding the leaves longitudinally of and relative to said rollers, the rocking axis of said bearing being adjacent an end of the other roller and extending transversely of said rollers, and a device adjustable for varying the gripping effect of said rollers on the leaves 95
10. A tobacco stemming machine having, in combination, a pair of rollers adapted mutually to cooperate to grip the stems of the leaves to be stemmed, means adapted to 100 rotate said rollers, means adapted to convey the leaves to be stemmed for cooperating with said rollers to effect stemming, an automatically rockable bearing in which one of said rollers is journaled for rotation, each of said rollers having threads at one end for feeding the leaves longitudinally of and relative to said rollers, the rocking axis of said bearing being adjacent an end of the other roller and extending transversely of said rollers, and a roller tensioning device including a balance weight upheld by said bearing and adjustable to different positions relative to said rockable bearing. 105
11. A tobacco stemming machine having, in combination, a pair of rollers adapted 110 mutually to cooperate to grip the stems of the leaves to be stemmed, means adapted to 115 rotate said rollers, means adapted to convey the leaves to be stemmed for cooperating with said rollers to effect stemming, and an automatically rockable bearing in which one of said rollers is journaled for rotation, each of said rollers having threads at one end for feeding the leaves longitudinally of and relative to said rollers, the rocking axis of said bearing being adjacent an end of the other roller and extending transversely of said rollers. 120
12. A tobacco stemming machine having, in combination, a pair of rollers adapted 125 mutually to cooperate to grip the stems of the leaves to be stemmed, means adapted to 130 rotate said rollers, means adapted to convey the leaves to be stemmed for cooperating

with said rollers to effect stemming, an automatically rockable bearing in which one of said rollers is journaled for rotation, each of said rollers having threads at one end [5] for feeding the leaves longitudinally of and relative to said rollers, the rocking axis of said bearing being adjacent an end of the other roller and extending transversely of said rollers, the threaded surface of one roller being tapered and that of the other cylindrical, and a device adjustable for varying the gripping effect of said rollers on the leaves therebetween.

10 In testimony whereof he hereunto affixes
15 his signature.
